WASHING MACHINE AGITATOR

Thomas R. Smith, Newton, Iowa, assignor to The Maytag Company, Newton, Iowa, a corporation of Delaware

Filed Sept. 26, 1966, Ser. No. 4,023

Term of patent 14 years

(Cl. D49—1)

FIGURE 1 is a perspective view of a washing machine agitator showing my new design;

FIGURE 2 is a side elevation view of the washing machine agitator shown in FIGURE 1;

FIGURE 3 is a top plan view of the agitator shown in FIGURE 1; and

FIGURE 4 is a sectional view of one of the agitator vanes of the agitator of FIGURE 1 as taken along line 4—4 of FIGURE 3.

The dominant features of my design reside in the portions shown in full lines.

I claim:

The ornamental design for a washing machine agitator, as shown and described.
